CLAIM

The ornamental design for a plastic container, as shown and described.

DESCRIPTION

FIG. 1 is a perspective view of a plastic container showing our new design;

FIG. 2 is a front elevational view thereof, the views rotated 72°, 144°, and 216°, and 288° clockwise from the front view being identical except for the unclaimed threads;

FIG. 3 is a rear elevational view thereof;

FIG. 4 bottom plan view thereof; and,

FIG. 5 top plan view thereof.

The broken lines shown in the drawing views are included for the purpose of showing environmental structure that forms no part of the claimed design.
